W. W. WATSON

SUSPENSION

Filed Sept. 11, 1922

UNITED STATES PATENT OFFICE.

WILLIAM W. WATSON, OF JAMESTOWN, NEW YORK.

SUSPENSION.

Application filed September 11, 1922. Serial No. 587,403.

To all whom it may concern:

Be it known that I, WILLIAM W. WATSON, a citizen of the United States, residing at the city of Jamestown, in the county of Chautauqua and State of New York, have invented certain new and useful Improvements in Suspensions, of which the following, taken in connection with the accompanying drawings, is a specification.

10 This invention relates to an improvement in suspensions, and more particularly to that type of extensible suspension used in connection with the drawers of a cabinet or other article of furniture to support the 15 drawers in any position.

One object of this invention is to provide a suspension which moves progressively with relation to the drawer which rests upon it, in other words, the suspension 20 moves approximately one half as far as the drawer so that in all positions the inner half of the portion of the drawer projecting from the cabinet is supported by the suspension. This results from the provision 25 of rollers mounted upon the suspension travelling over the cabinet side rails and imparting a movement of translation to the suspension.

Another object is to provide a suspension 30 having sets of rollers between which the drawer guides are inserted certain of said rollers being so mounted that the drawer guides regardless of their thickness are firmly gripped.

35 A further object of this invention is to provide a suspension which will form a rigid support for the drawer when partly or fully extended, said suspension being equipped with rollers which carry the 40 drawer and certain of which are lowered when the drawer is closed, allowing the rear end of the suspension to bear directly against the side rails of the cabinet, thus increasing a resistance to any tendency of 45 the drawer to slide open.

A still further object of this invention is to provide in each of the side plates by which the suspension is supported, a transverse depression which receives one of the 50 rollers on the suspension when the drawer is fully closed.

Other objects will appear from a consideration of the following description of the

drawing which forms a part thereof, and in which—

55 Figure 1 is a perspective view of a suspension embodying this invention.

Figure 2 is a perspective view of a drawer intended to be carried by said suspension.

60 Figure 3 is a transverse cross section of the drawer and suspension assembled in a vertical cabinet.

Figure 4 is a longitudinal section taken along the line 4—4 of Fig. 3 showing the 65 drawer closed.

Figure 5 is a view similar to Fig. 4 with the drawer fully extended.

Figure 6 is a corresponding view with the 70 drawer partly open, and

Figures 7 and 8 are detail cross sections taken along the lines 7—7 and 8—8 of Fig. 4.

75 Referring to the drawings, the reference numeral 10 is used to designate a suspension which is mounted upon side rails 11 fixed in a cabinet 12 and which carries a drawer 13. The suspension 10 comprises side frames 14 connected by front and rear cross bars 15 and 16, which rest on and are rigidly secured to the lower horizontal flanges 17 of the frames 14. Each side frame 14 has in addition to the flanges 17 an intermediate horizontal section 18 connected to the flanges 17 by a vertical section 19. From the outer edge of the section 18 projects a vertical flange 20.

80 Rotatably mounted on studs 21, 21^a projecting from the outer face of the vertical sections 19 are the front rollers 22, the intermediate rollers 23 and the rear rollers 24. The outer faces of the rollers 22 and 23 are provided with central depressions in which the flat heads of the studs lie. This construction is not essential, but is used in order to permit the use of rollers having a wide bearing surface.

85 The heads of the studs 21^a which carry the rollers 23 are in this construction made smaller in diameter than the depression so that the roller has a limited movement transversely of the stud. Figures 7 and 8 90 of the drawing illustrate the relation of the rollers and studs and the movement of the roller 23 transversely of the stud 21^a. Referring to those figures, it will be noted that 95

- the shank of the stud has a smaller diameter than the central opening through the roller and since the head of the stud is smaller than the depression, the roller can shift 5 transversely of the stud until the shank rests on the lower face of the central opening or the lower side of the depression wall of the roller 23 bears against the head of the stud 21^a.
- 10 The purposes of this construction will be disclosed hereinbelow. The rollers 22 and 23 extend through slots 25 in the section 18 above the upper face of the section, and carry the drawer 13. The rear roller 24 is 15 smaller in diameter than the rollers 22 and 23 and acts solely to support the suspension.
- Rotatably mounted on the stud 21^b projecting from the inner face of each vertical flange 20 above the roller 23 is a roller 26 20 and behind each roller is fixed a stop plate 27 which projects outwardly over the flange 20. The rollers 26 are similar to the roller 22 while the stud 21^b is similar to the stud 21. The relation of the roller 26 to the stud 25 21^b is therefore similar to that between the roller 22 and the stud 21, as shown in Fig. 7.
- The side rails 11 are rigidly secured to the cabinet 12, each having a horizontal flange 30 on which the rollers 22 and 23 run, and 30 at the rear end a second horizontal flange 31 above and parallel to the flange 30 against the under side of which the rear roller 24 bears. The rollers 24 and flanges 31 co-act in the usual way to prevent the front end of 35 suspension from tipping down. The portion 28 of the horizontal section 18 of the suspension back of the rollers 23 and 26 extends over the flanges 31 and is normally out of contact therewith.
- 40 Formed in the flange 30 of each plate 11 is a depression 32 in which the rollers 23, due to their movement on their shafts rest when the drawer is closed. Since up to that time the suspension 10 has been supported by the rollers 22 and 23, the result 45 of this will be to cause the suspension to tilt on the rollers 22, lowering the rollers 24 out of contact with the side rail flanges 31. If the depressions 32 are of sufficient depth 50 the rollers 24 will rest on the flanges 30 and at the same time the end of the portion 28 will rest upon the upper face of the flange 31. Thus any tendency of the drawer 55 to slide open will be impeded by the inertia both of the rollers 23 due to their position in the depressions 32 and of the portions 28 of the suspension due to their contact with the flanges 31.
- The drawer 13 is of the usual construction 60 having a horizontally flanged guide 40 along each side which, when the parts are assembled, is inserted between the rollers 23 and 26. Since the rollers 23 are capable of a transverse movement on their studs 21^a 65 the guides will be gripped firmly regardless

of the thickness of the material from which they are made. At the bottom of the drawer is provided a catch or blister 41 which engages the front cross bar 15 of the suspension 10 when the drawer is fully extended as 70 in Figure 5.

At the front and rear of the cabinet 12 are pilasters 50 which carry the side and rear plates 51 and the side rails 11. The stops 27 on the suspension strike the front 75 pilasters 50 when the drawer is fully extended.

When assembling the suspension is first mounted on the rails 11. The drawer 13 is now positioned upon the suspension, the 80 guides 40 being inserted between the rollers 23 and 26 with the catch 41 behind the cross bar 15.

Considering the drawer to be closed as in Fig. 4, the following will occur as it is 85 opened. The first pull causes the rollers 22 and 23 to rotate on their studs, and since they are mounted on the suspension, they move longitudinally, the rollers 23 leaving the depressions 32 and raising the rear end 90 of the suspension out of contact with the flanges 31 of the rails. When the drawer is fully extended as in Fig. 5, the catch 41 strikes the cross bar 15 of the suspension, and at the same time the stops 27 strike the front pilasters 50. Since the guides 40 are firmly gripped by the rollers 23 and 26 and the rollers 23 are held by the weight of the drawer against the side rails 11 as the 95 drawer is opened the guides will cause the 100 rollers 23 to rotate on their studs 21^a. The rotation of the rollers 23 on the studs will, of course, result in a movement of translation which is transmitted by the studs 21^a to the suspension 10 in which they are fixed. This movement of the suspension will be 105 continuous and progressive as the drawer is opened but by reason of the fact that the studs 21^a are approximately half way between the rails 11 and the guides 40 the suspension will move only half as far as the 110 drawer.

While one embodiment only has been shown and described, I am not to be limited thereto since other embodiments may be made without departing from the spirit and scope of this invention as set forth in the 115 following claims.

Having thus set forth my invention, what I claim as new and for which I desire the 120 protection of Letters Patent is:

1. In a cabinet having side rails provided with upper and lower flanges, a suspension mounted upon said rails, a drawer supported by said suspension, a pair of rollers on said suspension, other rollers on said suspension certain of which bearing normally against the lower faces of said upper flanges while a portion of said suspension extends above and out of contact with said flanges, depres- 125 130

- sions in the lower flanges of said side rails which said first named pair of rollers enters when the drawer is closed, whereby the extending part of said suspension will rest 5 upon said upper flanges.
2. In a cabinet having side rails provided with upper and lower flanges, a suspension mounted on said rails, a drawer supported by said suspension, front and intermediate 10 sets of rollers on said suspension bearing on said lower flanges, the intermediate set of rollers being movable transversely of said suspension, rear rollers on said suspension normally bearing against the lower faces of 15 said upper flanges while a part of said suspension lies above said flanges, depressions in the lower flanges of said side rails which said intermediate rollers enter when the drawer is closed, whereby the suspension
- tilts on the front rollers, the rear rollers 20 move away from the lower faces of said upper flanges and the part of said suspension above said upper flanges rests thereon.
3. A drawer suspension comprising side frames, each consisting of a vertical flange, 25 a vertical section and a horizontal section connecting said vertical flange and vertical section, rollers mounted on the outer faces of said vertical sections, slots in said horizontal sections through which said rollers 30 project, rollers mounted on the inner faces of said vertical flanges above and resting upon certain of said first named rollers, and cross bars connecting said side frames.

In testimony whereof I have affixed my 35 signature.

WILLIAM W. WATSON.
